UNITED STATES PATENT OFFICE.

MALON E. FREEMAN, OF COLBY, KANSAS, ASSIGNOR OF ONE-FOURTH TO LESTER C. HOWARD AND ONE-FOURTH TO FLOYD CASSELMAN, BOTH OF HALFORD, KANSAS.

RAIL-JOINT.

1,146,862.

Specification of Letters Patent. Patented July 20, 1915.

Application filed November 19, 1912, Serial No. 732,318. Renewed December 15, 1914. Serial No. 877,448.

To all whom it may concern:

Be it known that I, MALON E. FREEMAN, a citizen of the United States, residing at Colby, in the county of Thomas and State 5 of Kansas, have invented new and useful Improvements in Rail-Joints, of which the following is a specification.

The present invention relates to improvements in rail joints.

10 In carrying out my invention it is my purpose to provide a rail joint including, in combination with rail ends a rail chair and a fish plate, the connection between the chair, rails and fish plates being such as to 15 effectively sustain the rails against downward or lateral movement and to provide a smooth, unbroken surface at the meeting ends of the rails, and thus forming what may be termed a continuous rail.

20 A still further object of the invention is the provision of a device of this character, including a rail chair and a fish plate, and wherein, a single securing element may be employed for effectively retaining the rail 25 ends upon the chair and upon the fish plate.

With the above objects in view and others of a similar nature which will appear as the description progresses, the improvement resides in the construction, combination and 30 operative arrangement of parts set forth in the specification and falling within the scope of the appended claims.

In the drawings, Figure 1 is a perspective view of the meeting ends of a pair of rails 35 connected in accordance with the present invention. Fig. 2 is a transverse section, taken approximately upon the line 2—2 of Fig. 1. Fig. 3 is a horizontal sectional view upon the line 3—3 of Fig. 2. Fig. 4 is a 40 sectional view upon the line 4—4 of Fig. 3. Fig. 5 is a perspective view of the rail chair. Fig. 6 is a similar view of the fish plate. Fig. 7 is a perspective view of one of the rail ends.

45 Referring now to the drawings in detail R—R designate the rails. These rails are each provided with enlarged webs 1, which have their opposite faces vertically straight. The enlarged rail ends, are cut centrally 50 and longitudinally to provide vertically straight inner faces or walls 2, and inclined walls 3 at either end of the straight faces. The extreme ends are provided with vertical walls 5, forming a wedge-like end. The 55 walls 3 terminate in shoulders 6, the said

shoulders being beveled at an opposite inclination to the ends 5, and whereby one of the said shoulders will provide what may be termed a pocket for the end 4 of the co-acting rail. By such an arrangement it will be noted that the joint of the rail ends provides substantially a tongue, and a groove to receive the tongue and by providing the vertically straight walls 2 it will be further noted that the rail ends may contract or expand without interfering with the alinement of the upper faces of the rails or with the side faces of the heads of the rails. The portions of the rail ends provided with the enlarged heads have registering openings, 60 the same adapted to receive securing elements, such as the usual bolts 7 and nuts 8 therefor. The webs proper of the rails, at a suitable distance away from the enlargements thereof are also formed with openings 9, the said openings being adapted to receive a similar connecting element as will presently be fully set forth. Also the shoulders, which may be designated by the numerals 10 and which are provided between 65 the webs and the enlargements of the rails 70 perform a function which will hereinafter be alluded to.

The numeral 12 designates the chair for the rail ends. This chair comprises a base 85 portion which is horizontally straight and the said base has integrally connected therewith a vertical longitudinal extension 15. The ends of the extension are enlarged as at 16, to snugly engage with the inner sides 90 of the rail webs, adjacent their enlargements, and the said enlarged portions of the chair are arranged adjacent the shoulders 10 of the rails. The portion of the vertical extension 15, between the said enlarged ends 95 is arranged a suitable distance below the upper edges of the ends, and the said vertical portion is formed with depressions arranged adjacent the openings in the enlarged ends of the rails to permit the insertion or adjusting of the securing elements, and the enlarged ends are also provided with openings which register with the openings 9 in the rail webs. The opposite longitudinal side of the base of the chair 12 100 is upset to provide an outwardly inclined flange 18.

The numeral 19 designates an angular fish plate. This fish plate has its outer and lower angular member centrally provided 110

with an opening 20, the said opening adapted to register with a similar opening provided in the base of the chair 12, the said openings being adapted for the reception of 5 a bolt member 21 and a nut member 22, therefor, and whereby the fish plate is effectively sustained upon the chair and against the rails as will presently be more fully set forth. The outer edge of the lower 10 flange member of the fish plate is beveled as at 23, the inclination thereof being opposite to that of the inclined outer flange of the chair, and the said inclined flange is adapted to coöperate with the inclined edge of 15 the fish plate. The fish plate has its inner face centrally reduced as at 24, and whereby the said fish plate may snugly engage with the enlarged web faces of the rail ends, and the shoulders 25, adjacent the ends of the 20 said fish plate are adapted to snugly engage with the rail webs adjacent the shoulders 10 thereof. The enlarged ends of the vertical flange of the fish plate are provided with openings which are adapted to register 25 with the openings in the rail webs, and with the openings provided in the enlargements or shoulders formed upon the ends of the vertical member of the rail chair, the registering openings being adapted to receive 30 securing bolts 26 and nuts 27 for the bolts. The shoulders 25 of the fish plate are adapted also to underlie the heads of the rails, and the vertical member of the fish plate is provided with a reduced longitudinally extending portion 29, adapted to contact with 35 the outer faces of the rail heads. The vertical member of the fish plate is further provided with centrally arranged openings which are adapted to register with the openings provided in the enlarged webs of the 40 rails ends, and these openings are, of course, adapted to receive the usual securing nuts and bolts.

In assembling the parts, the rail ends are 45 first brought together on the base of the chair and moved thereon until their base flanges are arranged beneath the angular or overlying flange provided upon one side of the said chair, and also have their webs engage 50 with the enlarged ends provided upon the vertical wall formed upon the overlying flange. When the parts are so arranged the fish plate is positioned at an angle, with its inner depressed portion, and the shouldered 55 walls provided thereby brought into engagement with the upper portions of the enlargements of the rails beneath the heads of the rails. This brings the lower edge of the 60 beveled portion 23 of the fish plate in register with the upper edge of the inclined flange of the chair, and it will be noted that a downward pressure upon the lower and horizontal flange of the fish plate will force the said fish plate tightly upon the chair, so as to bring the opening 30 into register

with the opening provided in the base of the fish plate, and to permit of the insertion of a securing bolt and nut therefor. When the parts are thus assembled it will be apparent that the additional securing elements 70 may, if desired, be dispensed with, as the shouldered ends of the fish plate and rail chair effectively engage the webs of the rails, as well as the heads and base flanges of the said rails, adjacent the shoulders provided 75 between the webs and the enlargements of the webs, so that a separation of the parts, without the removal of the securing means between the fish plate and the chair, is effectively obviated. However, I 80 have found it preferable to employ the additional securing elements above referred to, as the same add to the security of the joint, inasmuch as should the first named securing elements become dislodged the remaining elements will effectively retain the joint in proper condition. It is to be understood that the shouldered or enlarged ends of the chair and of the fish plate do not contact with the shoulders provided between 85 the webs and the enlargements therefor so that contraction or expansion of the rails is not thus interfered with.

From the foregoing description, taken in connection with the accompanying drawings, the simplicity and advantages of the device, will, it is thought, be apparent to those skilled in the art to which such inventions appertain, without further detailed description.

Having thus described the invention, what I claim is:—

1. The combination with rail ends, said rail ends being provided with web enlargements, a chair for the rails, said chair having its base provided with an angular overlying flange which is adapted to engage with the base flanges of the rail ends, the overlying flange being provided with a vertical upset portion, the ends of which have 110 their inner faces enlarged and adapted to contact with the webs of the rails adjacent the enlargements thereof, an angular fish plate for the opposite faces of the rail ends, said fish plate having its vertical wall provided with shouldered ends, the said ends adapted to engage the webs of the rails adjacent their enlarged portions, and means for connecting the fish plate and chair with the rails.

2. The combination with the meeting ends of railway rails, each having web enlargements, a chair for the rails, said chair having one of its sides upset and provided with an angular flange which terminates in a vertically longitudinally extending wall, the ends of the said wall having their inner faces enlarged and adapted to abut against the balls of the rails, and the webs thereof adjacent the enlargements of the webs, when

the rails are positioned upon the chair, the base of the chair having its opposite longitudinal edge provided with an angular flange, an angular fish plate, said fish plate 5 having its inner face provided adjacent its ends with enlargements which are adapted to engage with the webs of the rails adjacent the enlargements thereof, the horizontal member of the angular fish plate having 10 its outer edge beveled to co-act with the inclined upset flange of the chair, means for connecting the chair with the horizontal member of the fish plate, and means for connecting the chair and fish plate with the 15 webs of the rail, and to the web enlargements of the rails.

3. In a rail joint, co-acting rail ends having their outer faces provided with web enlargements, the said rail ends being approximately centrally provided with straight longitudinally extending walls, each of the said walls being inclined outwardly toward the end of the rail, and the said end of each of the rails being beveled, the said walls being further provided with a beveled portion which is inclined toward the opposite face of the rail, and which terminates in a beveled wall which provides a pocket, a chair 20 for receiving the rail ends, said chair having one of its edges provided with an angular flange which overlies its base and which is adapted to receive the base flanges of the 25

rails, the said beveled flange having an upset portion, the said upset portion having its inner face, adjacent its ends enlarged to 30 provide shoulders which are adapted to abut the webs of the rails, and to underlie the balls of the rails, the chair having its opposite longitudinal edge provided with an outwardly inclined upset flange, an angle fish 35 plate, said fish plate having its vertical face depressed to provide its ends with shoulders, and the said shoulders adapted to engage with the webs of the rails adjacent their enlargements and to underlie the balls 40 of the rails, the said fish plate having its inner face provided with a longitudinally extending depression which provides angular walls which engage both beneath the balls and the outer faces of the balls of the rails, 45 the horizontal member of the fish plate having its longitudinal edge beveled from its bottom outwardly toward its top, the said inclined edge adapted to co-act with the inclined flange of the chair, means for securing the fish plate to the base of the chair and connecting means for the fish plate, the 50 rails and the chair.

In testimony whereof I affix my signature in presence of two witnesses.

MALON E. FREEMAN.
